United States Patent Office

Des. 180,172
Patented Apr. 30, 1957

180,172

MAGNETIC CLIP HOLDER

John E. Bartlett, El Cerrito, Calif.

Application September 11, 1956, Serial No. 42,901

Term of patent 14 years

(Cl. D17—3)

Fig. 1.

Fig. 2.

Fig. 3.

Figure 1 is a rear perspective view of a magnetic clip holder showing my new design, a metal rule supported thereby being illustrated in dash-dot lines;

I claim:

The ornamental design for a magnetic clip holder, substantially as shown and described.
